INVESTING METHOD

John Frei, Jr., Chicago, Ill.

Application November 9, 1944, Serial No. 562,767

2 Claims. (Cl. 22—193)

1

This invention relates to molds for use in casting various articles, and has to do with a method of investing patterns with mold forming material in the production of such molds.

It is known, particularly in the centrifugal casting art, to produce casting molds by investing heat destructible patterns, mounted in mold flasks, with a settable mold forming material in fluid form, permitting the investment material to set to the proper extent, after which the body of investment material and the pattern therein are properly heated so as to destroy and remove the pattern, thus providing a mold having a casting cavity therein conforming to the pattern. Much difficulty has been encountered in producing molds in this manner due, in large measure, to the presence of air in the investment material. This air frequently forms bubbles in contact with the pattern, with the result that the cast article has imperfections which in many cases render it unfit for its intended use. That is particularly true where precision is required.

Various attempts have been made to overcome the above referred to difficulty resulting from the presence of air in the investment material. It has been proposed to invest the patterns by delivering the investment material to a stationary mold flask while the latter is within a space maintained under a suitable vacuum and, as soon as the flask has been properly filled, to admit atmospheric air to the space and thereby immediately relieve or break the vacuum. When the atmospheric air is admitted, the investment material is in a rather loose and unpacked condition, due to the effect of the vacuum, the air enters the space under considerable velocity and a portion of the entering air penetrates into the investment material. As a result, air is trapped in the investment material and a portion of this trapped air may, and frequently does, find its way to the pattern to which it attaches itself in the form of bubbles. This procedure offers no assured solution of the difficulty. It has also been proposed to subject a body of the investment material to a vacuum until ebullition ceases, immediately break the vacuum by admission of atmospheric air, carefully introduce the pattern into the investment material, subject the investment material with the pattern therein to vacuum and remove the pattern and let it set until the coating of investment material has hardened, thereby providing it with a primary investment. That operation may be repeated and the pattern with its coating of primary investment may then be subjected to a secondary investment in mate-

2

rial which has been subjected to vacuum in the same manner as for the primary investment. Such a procedure obviously is time consuming and expensive. Also, it does not assure that all of the air is removed from the investment material, particularly if the body of such material subjected to vacuum is of considerable depth, as frequently is necessary. In introducing the pattern into primary investment material it is difficult to avoid introducing air also, in direct contact with the pattern, and this air attaches itself to the pattern in the form of bubbles. A further proposal comprises subjecting a body of investment material to a vacuum while being vibrated, dipping the pattern into the treated material to provide it with a primary investment coating, and then completely investing the coated pattern with a secondary investment material. Here, again, there is the difficulty that in introducing the pattern into the primary investment air is also introduced and attaches itself to the pattern in the form of bubbles. Further, subjecting a mass of investment material to a vacuum, even when accompanied by vibration, does not suffice to remove all of the air from the material, particularly if the mass or body of investment material is of considerable depth, as is frequently necessary. In such cases, the upper portion of the body of investment material will swell and bubble or boil and most of the air may be removed from that portion, but the lower portion of the mass will be but little affected and most of the air originally present in the lower portion will remain there. Vibration of the mass causes packing, which retards escape of air from the lower portion thereof and aggravates rather than alleviating the condition which it is sought to remedy. None of the procedures above referred to has to my knowledge provided a satisfactory solution of the problem of removing air from investment material to be used in the production of molds for casting, nor am I aware of any presently known procedure which accomplishes that desirable result in an assured and satisfactory manner.

My invention is directed to a method of investing patterns in a manner which avoids the above noted objections to the present methods and effectively guards against the presence of air bubbles in contact with the patterns. More specifically, I provide a method whereby a pattern may be completely invested in a single operation with assurance that no air bubbles will be formed in contact with the pattern, which effects a material saving in time and work compared to the

present practice, in addition to rendering possible assured precision casting. Briefly, as to the method of my invention, I have discovered that by delivering the investment material to the mold flask while subjecting it to a vacuum effective for removing the air from the material, and packing the air free material about the pattern in the flask as it is delivered to the latter, the formation of air bubbles in contact with the pattern is completely eliminated. Preferably, when the flask has been properly filled with the packed air free investment material, the vacuum is gradually reduced until the pressure to which the body of investment material is subjected has been increased to atmospheric. That avoids risk of air entering the body of investment material, as might occur if the pressure were abruptly raised to atmospheric and for that reason is desirable, though not essential to the broader aspects of the method of my invention. Further objects and advantages of my invention will appear from the detail description.

In the drawings:

Figure 1 is a semi-diagrammatic view, partly in section and partly in elevation, of investing means embodying my invention, illustrating also the method of my invention; and

Figure 2 is a view similar to Figure 1, but after completion of the investing operation and showing the bell jar in elevation and in its raised position.

I have shown, by way of example, preferred means for performing the method of my invention. This means comprises a suitable board or platform 5 hinged at one side, at 6, to a suitable support 7. A bracket 8 is secured to the underface of platform 5 adjacent and centrally of the other side thereof, i. e., the side opposite to its hinged side, and carries a roller 9 which contacts an eccentric 10 secured upon the shaft of an electric motor 11 mounted upon a base 12, which may be mounted upon support 7 below platform 5. Two tension springs 13 are anchored at their upper ends to platform 5, at the front and adjacent each end thereof, the lower ends of these springs being anchored to base 12. The platform 5 is disposed horizontally and springs 13 hold roller 9 in pressure contact with eccentric 10 so that platform 5 is vibrated vertically when the motor 11 is in operation, the eccentric 10 being so formed that but slight vertical movement is imparted to platform 5.

A vacuum pump unit 14, of known type, has its intake connected by a length of flexible hose 15 to a tube 16 secured at its upper end portion through platform 5, this tube being provided with a suitable valve 17 of known type. A second tube 18 is secured to platform 5 and is connected to a vacuum gauge 19 of known type, this second tube being provided with a valve 20 of known type. Preferably, though not necessarily, a third tube 21 is secured to platform 5 and extends outwardly therebeyond, this third tube being provided at its outer end with a valve 22 of suitable known type.

The upper face of platform 5 is provided with a covering or pad 23 of rubber or other suitable material of a character to form a fluid tight seal with a flange 24 at the lower end of a glass cover or bell jar 25 seating upon pad 23. The ends of the tubes 16 and 18 and 21, when the latter tube is used, are so disposed as to open into the bell jar 25 when the latter is properly positioned upon platform 5, as shown in Figure 1.

At its upper end bell jar 25 is provided with a short neck 26 defining an opening which receives

a rubber stopper 27 having a central opening for reception of a tubular neck or stem 28 of a glass funnel 29, neck 28 being controlled by a conical plug or cock 30 mounted therein adjacent the lower end of funnel 29 and disposed a short distance above stopper 27. After the neck of funnel 29 has been inserted to the proper extent through stopper 27, the latter is pressed tightly into neck 26 of bell jar 25 so as to be compressed about neck 28, forming a fluid tight seal therewith and also gripping neck 28 frictionally, effective for supporting the funnel 29 in position, the stopper 27 also forming a fluid tight seal with neck 26 of bell jar 25; as will be readily understood. Bell jar 25 is disposed between the depending arms of a frame or yoke 31 of elongated inverted U shape, in which yoke the bell jar is secured by thin metal straps 32 extending circumferentially about the bell jar and secured at their ends to the arms of yoke 31 by known means effective for drawing the straps 32 tightly about the bell jar. In that manner the bell jar 25 is secured in yoke 31 for movement therewith. A cable 33, preferably a wire cable, is suitably secured at one end to the upper end of yoke 31 centrally thereof, from which cable 33 passes over guide pulleys 34 and 35. A counterweight 36 is attached to the other end of cable 33 and tends to raise the yoke 31 and the parts carried thereby. A stop 37 is suitably secured on the run of cable 33 extending between pulley 35 and counterweight 36, the cable 33 below stop 37 passing between the fingers of a forked member 38 suitably secured to a support 39, on which the pulleys 34 and 35 may also be mounted. The stop 37 cooperates with member 38 to limit the extent to which yoke 31, together with the parts carried thereby, is raised by the counterweight 36, as will be understood.

The platform 5 is adapted for reception of a mold flask 40 fitting tightly at its lower end in a flanged base 41 which has a flat underface and seats upon platform 5 within the area between the ends of the tubes 16, 18 and 21, which are, of course, properly disposed to that end. The base 41 is provided with a central upwardly projecting element 42 having therein recesses for reception of the lower portions of one or more sprue pins 43. A frusto-conical element 44 is suitably secured to the upper ends of pins 43, this element and element 42 of base 41 tapering upward as shown. Element 44 is secured to the lower end of a pattern 45, shown as of simple form for purposes of illustration. In practice, pins 43, element 44 and pattern 45, are formed of a suitable heat destructible material, such as a low fusing alloy or a synthetic resin, wax, or the like. Preferably, the pattern 45 and element 44 and the sprue pins 43 are formed of styrene, as separate elements, and are secured together by moistening appropriate areas thereof with a solvent, such as alcohol, so as to soften them, and pressing the surfaces together. Obviously, the elements referred to may be otherwise formed and secured together. The mold flask 40 preferably is cylindrical and is formed of an alloy steel capable of resisting high temperatures. The flask 40 is provided with a liner 46 of asbestos, or other suitable material of like character, which extends upward beyond the open upper end of the flask.

The funnel 29 contains a suitable quantity of a settable refractory investment or mold forming material 47 in liquid form. Various investment materials of this character are known and any

suitable known investment material may be used in practicing my invention. I have found the investment material disclosed in Patent No. 2,027,932, issued to Arthur B. Ray, to be satisfactory. After the flask 40 with the pattern mounted therein as above has been properly positioned upon platform 5, the bell jar 25 is disposed about flask 40 with flange 24 seating upon the rubber pad 23. The vacuum pump unit 14 is then set into operation and creates a partial 10 vacuum within the bell jar 25, which is then held tightly seated upon platform 5 by atmospheric pressure. In the continued operation of unit 14 the appropriate degree of vacuum is produced within the bell jar 25 and, by proper adjustment of valve 17, is maintained. The degree of vacuum to be produced and maintained within the bell jar 25 need not be great and depends upon the particular investment material being used. The amount of vacuum should be sufficient to assure complete withdrawal of air from the investment material without causing objectionable volatilization of liquid constituents thereof, and may readily be determined by experiment. When the proper degree of vacuum within bell jar 25 has been attained, the stop cock 30 is opened and the investment material 47 flows through neck 28 of funnel 29 and is delivered from the lower end of neck 28 into mold flask 40 through the open upper end thereof. As the stream of investment material is discharged from the lower end of funnel neck 28, it is exposed to the vacuum within bell jar 25 which acts to break up or expand this stream radially so as to immediately remove all of the air therefrom, the investment material being then delivered to the flask 40 in more or less spray form instead of in the form of a solid stream. In that connection, it will be noted that the diameter of the entering stream of investment material is slight relative to the diameter of the mold flask 40, so that the vacuum maintained within the bell jar 25 is effective for spreading or breaking up the entering stream of investment material and removing the air therefrom in the manner stated. At the time of opening the cock 30, or prior thereto, the motor 11 is set into operation so that the flask 10 is vibrated during delivery thereto of the air free investment material. In that manner the investment material is freed of air and this air free material is packed in the mold flask about the pattern therein as it is delivered to the flask. After the flask 40 and the liner 46 has been filled with investment material to the proper depth, which is such that the investment material extends upward within liner 46 a material distance above the flask 40, the cock 30 is closed, it being noted that the amount of investment material in funnel 29 should be considerably in excess of the amount required for investing the pattern in the manner stated, so as to prevent entry of atmospheric air through the neck 28 of funnel 29 to bell jar 25. After the cock 30 has been closed, atmospheric air is admitted gradually to the bell jar 25 until the pressure therein becomes equal to atmospheric pressure, or but slightly lower than atmospheric. The admission of atmospheric air to the bell jar 25 may be through the tube 21 under control of valve 22, in which case valve 17 is closed, it being understood that the vacuum pump unit 14 is stopped when flask 40 and liner 46 have been filled to the proper depth with the investment material. Alternatively, the tube 21 may be omitted and valve 17 may remain open

when unit 14 is stopped, slow leakage of air through unit 14 serving to gradually relieve the vacuum within the bell jar 25. In either case, the relief of the vacuum within the bell jar 25 should occupy a period of from 15 to 20 seconds. During that time the motor 11 remains in operation and vibration of the flask 40 continues so that the investment material is firmly packed within the flask about the pattern before relief of the vacuum within the bell jar 25. In fact, the major portion of the investment material is firmly packed within the flask 40 by the time the latter has been filled to the proper depth and prior to closing of the cock 30. That obviates the risk of air entering the investment material within flask 40 to any appreciable depth, even though the vacuum within the bell jar be broken abruptly. Preferably, however, I usually break the vacuum gradually in the manner stated, as a further safeguard against possible entry of air into the investment material within the mold flask. During the admission of air to the bell jar 25 for breaking the vacuum therein, or prior to breaking the vacuum within bell jar 25 in any other suitable manner, the investment material 47 within funnel 29 is replenished by an amount equal to that discharged from the funnel in the investing operation, all of the material within the funnel 29 being then stirred so as to assure uniform mix thereof. When the pressure within the bell jar 25 becomes equal to atmospheric pressure, or slightly less than atmospheric pressure, the counterweight 36 raises the yoke 31 and the parts carried thereby so as to position the bell jar 25 a proper distance above mold flask 40, as shown in Figure 2, so as to provide an unobstructed space above platform 5 for removal of flask 40 and the invested pattern therein, and for positioning upon platform 5 a second flask with a pattern therein to be invested. The bell jar 25 is then again seated upon the platform 5 and the operation is repeated. The automatic raising of the bell jar clear of the invested pattern and flask leaves the operator's hands free and is conducive to expedition and facility in investing the patterns, of importance in quantity production.

After the pattern has been invested in the manner stated, the mold flask with the invested pattern therein may be subjected to further vibration for maintaining the investment material packed as it sets, and after the investment material has set to the proper extent the portion of the liner 46 above the flask 40 and the excess investment material therein is trimmed off. Thereafter the mold flask with the invested pattern therein is permitted to set until the investment material has properly dried, and the mold flask with the invested pattern therein is placed in a suitable furnace and heated to a temperature sufficient to destroy the sprue pins 43, the element 44 and the pattern 45, the mold flask being disposed at that time with the end having the pouring gate formed therein by element 42 of base 41 downward, it being understood, of course, that base 41 is removed from the mold flask 40 when the investment material therein has set to the proper extent. That provides a mold having therein a casting cavity conforming accurately to the pattern 45 and free of recesses or depressions such as would be caused by bubbles adhering to the pattern, this mold also having an outer pouring gate formed by the element 42 of base 41 and an inner pouring gate or reservoir formed by element 44, these two gates being connected by

restricted openings provided by the sprue pins 43. The mold formed in this manner constitutes the subject matter of my copending application for casting mold and method, Serial No. 731,697 filed February 28, 1947, and need not be further described here, since the particular construction of the mold forms no part of my instant invention. The mold may, of course, be of any other suitable construction within the broader aspects of my present invention.

By delivering the investment material to the mold flask in a stream subjected to a vacuum, the air is removed from the investment material and this air free material is packed in the mold flask about the pattern as it is delivered to the flask, whereby the possibility of air bubbles forming in contact with the pattern is eliminated. While I have referred to the removal of air from the investment material, it will be obvious that the method of my invention is effective for removing gases other than air and which would tend to form bubbles in contact with the pattern. Accordingly the term "air" as used herein is to be construed as including air proper and other gases which like air would incur the risk of forming bubbles in contact with the pattern, and the term "air" is used in that sense in the appended claims. The removal of air or other gases from the investment material in the manner explained above assures that the mold cavity will conform accurately to the pattern, rendering possible precision casting while also rendering possible investing of the pattern with a body of material sufficient to form the mold in a single operation. That contributes to relatively high speed operation in the production of the molds with a corresponding saving in cost of production of the cast articles while, as noted, assuring precision in casting of the articles. After the destructible pattern and associated elements have been destroyed and removed from the mold, as above, the heating of the mold may be continued until it has been raised to the proper temperature for casting, after which the casting operation may be performed in a suitable known manner.

As has been above indicated, and as will be understood by those skilled in this art, changes in details, may be resorted to without departing from the field and scope of my invention, and I intend to include all such variations, as fall within the scope of the appended claims, in this application in which the preferred form only of my invention has been disclosed.

I claim:

1. The method of investing a pattern to make a casting mold which comprises mounting a pattern in a flask, investing the pattern with a settable mold-forming material by delivering to the flask a stream of said mold-forming material in fluid form, subjecting the stream to vacuum as it is being delivered to the flask so as to break up the stream and remove air therefrom, and simultaneously vibrating the flask to cause a packing of the material about the pattern and to release from the material any air entrapped therein, said air being drawn off by reason of the vacuum.
2. The method of investing a pattern to make a casting mold, which comprises mounting a pattern in a flask closed at its bottom and open at its top, placing the flask and pattern therein in an enclosure, producing a vacuum within the enclosure, investing the pattern by delivering to the flask through its open top a settable refractory mold-forming material in fluid form in a downwardly flowing stream while maintaining said vacuum within the enclosure, thereby breaking up the stream and removing air from said material as it is delivered to the flask, vibrating said flask and the resultant air free material therein during delivery of the latter to the flask and while it is subjected to the vacuum, thereby packing the material about the pattern and, following pouring of the mold, increasing pressure within the enclosure at a rate to prevent penetration by incoming air of the body of material packed in the flask.
